DEVICE FOR PREFORMING CORRUGATED MATERIAL FOR LAMP SHADES

Albert H. Bien, Wynnewood, Pa.

Application October 11, 1949, Serial No. 120,636

2 Claims. (Cl. 93—1)

1

The present invention relates to the manufacture of lamp shades and more particularly to a device for preforming corrugated material ready for shaping about a lamp shade frame.

In the manufacture of lamp shades made of corrugated or fluted paper or like material, there has been heretofore a problem as to how to reshape and bend the corrugations so that the finished shade can be fitted about its frame without exposing broken corrugations and generally producing an unsightly effect. To overcome this disadvantage in manufacture it has been proposed to transversely slit or cut away the corrugations on a line of bend and use a tie string or cord to maintain the assembly. Such attempts have failed to solve the problem and have so weakened the material that the shade is lacking the durable characteristics of this type of article.

Some of the objects of the present invention are: to provide a novel means for preforming corrugated material in the manufacture of paper or like lamp shades; to provide a device for defining a line of bend in corrugated material which in assembled condition of the lamp shade exposes no unsightly changes in the flutes of the corrugations; to provide a device where a length of corrugated material can be effectively scored and bent along a predeterminedly located line without damaging the appearance of the material; to provide a device which simultaneously serves as a gauge for defining the width of the neck or collar of a lamp shade, and as a scoring and bending medium; and to provide other improvements as will appear hereinafter.

In the accompanying drawings, Fig. 1 represents a plan of a combined gauge, bending and scoring device; Fig. 2 represents a section on line 2—2 of Fig. 1; Fig. 3 represents a perspective of the device showing the placing of material for the scoring and bending operation; Fig. 4 represents a perspective of the device showing the carrying out of the scoring and bending operation; Fig. 5 represents a section of the material for a lamp shade prior to operation by the device; Fig. 6 represents a section of the material after operation by the device taken on the line 6—6 of Fig. 7; Fig. 7 represents a front elevation of the material after operation of the machine; Fig. 8 represents the completed material mounted to form a lamp shade; and Fig. 9 is a section longitudinally of the scored corrugation taken on the line 9—9 of Fig. 7.

Referring to the drawings, one form of the present invention comprises a device shown in

2

Figs. 1 to 4 for linear scoring and bending a length of corrugated paper 10 or other material suitable for use in making lamp shades. In the preferred form of the invention, the device comprises a flat metal bed plate 11 arranged for support on a table to lie in a horizontal plane as a support for such a length of corrugated paper as will form a lamp shade when its ends are brought together and fastened as a tubular assembly.

10 Lamp shades of this character are designed to fit about a wire skeleton frame having a small diameter ring at the top and a large diameter ring at the bottom. The shade to which the present invention relates is to have the appearance of two truncated cones arranged in superposed relation with ends meeting in a common plane just below the top small diameter ring, so that the latter is concealed within the relatively short collar formed by the upper truncated cone, and which latter is held in shape by the aforesaid top frame ring. The problem which has been solved by the present invention was how to line score and bend a length of corrugated paper so that the material could be bent along the scoring line to assume the desired outwardly flaring collar.

15 As a means for forming a straight edge for defining the score and bending line, a hold-down plate 12 is hinged at 13 to the front edge of the bed plate 11 so that it can be raised to permit placing of the length of material which has been 20 cut to the predetermined necessary length for a particular size of lamp shade. The width of the hold-down plate 12 is such as will cover the body of the material while leaving an end portion thereof of predetermined width exposed beyond the straight edge of the plate 12. Handles 14 are attached to the hold-down plate 12 for proper material control thereof.

25 In order to score and bend the corrugated material along the line defined by the straight edge of the hold-down plate 12, a bending strip 15 is hinged at 16 to the top of the bed plate 11 in such close proximity to the straight edge of the hold-down plate 12 as will locate a long edge of the strip 15 parallel to and substantially abutting the edge of the plate 12. When the strip 15 is in its initial or inoperative position, it lies in the same horizontal plane as the plate 12.

30 For the purpose of gauging the width of the material for the lamp shade collar, a flat strip gauge member 17 is adjustably mounted for sliding movement upon the strip 15 towards and away from the straight edge of the plate 12, and with which it has parallel relation. The spacing between the member 17 and the plate 12 determines

the selected width of the collar to be formed. This adjustment takes place through the provision of slots 18 in the member 17, the axes of which are respectively perpendicular to the straight edge of the plate 12. Bolts 20 fixed to the gauge member 17 project respectively through the slots 18 to receive wing nuts 21 or other position-locking means. Thus, by loosening the wing nuts 21 the gauge member 17 can be moved to provide a predetermined space between it and the straight edge of the plate 12, the spacing defining exactly the width of the collar for the particular shade being made. A handle 22 is fixed to the face of the gauge member 17 for grasping and lifting.

In operation the gauge member 17 is first set for the selected collar width and then fixed in place by tightening the nuts 21. Both the hold-down plate 12 and the strip 15 now lie in the same plane. The operator now raises the hold-down plate 12 to expose the face of the bed plate 11, and places a length of the corrugated material flat on the bed plate while at the same time moving it forward to bring its outer edge in contact with the set face of the gauge member 17. The hold-down plate 12 is now lowered and pressed into clamping relation with the body of the material, thereby defining a clean-cut line along the upper face of the material. While so held, the operator grasps the handle 22 and lifts the strip 15 to a substantially vertical position, whereby the exposed collar portion of the material follows the aforesaid movement and is scored as it turns about the straight edge of the plate 12 in the bending operation. With the linear bend line now properly formed, the length of material is removed from the machine and its two ends then overflapped and sealed together by any suitable adhesive. The tubular shade can now be fitted about the skeleton frame with the bend line coinciding with the upper frame ring where it is made fast by a ribbon or other decorative tape. When thus mounted, the contour of the shade is that of two truncated cones, one being superposed upon the other in inverted position so that the neck and body of the shade flare outwardly from the meeting line in pleasing symmetry.

By reference to Figs. 7 and 8, the novel result accomplished by the device will be evident and it should be noted that the corrugated ribs at one face of the material are each scored inwardly, as shown at 23, and thereby produce transverse V-shaped projections acting as reinforcement between the respective ribs of the opposite face of the material.

It will now be apparent that a complete unitary device has been devised for preparing a length of corrugated material for shaping into a lamp shade by so scoring and bending the material that a neck portion of predetermined width is provided without leaving unsightly slots or broken corruga-

tions, and which is readily mounted on a frame of the usual shape. In the foregoing description the use of the term "score" is used in the sense of notches as distinguished from cuts or slits.

Having thus described my invention, I claim:

1. In a device of the character described, a fixed support, a hold-down plate hinged to said support to move towards and away from the exposed face of said support and providing a space between said support and said face to receive a portion of the width of a length of corrugated material, the corrugations thereof being perpendicular to the free edge of said plate, a bending strip hinged to said support in close proximity to said edge to seat under the projecting width of said material to be bent along the line of said free edge, handle means on said plate for lifting said plate while said material is placed thereunder, handle means on said strip to line score and bend said material along the free edge of said plate, and a gauge member mounted on said strip to define the width of the projecting portion of said material.

2. In a device of the character described, a fixed support, a hold-down plate hinged to said support to move towards and away from the exposed face of said support and providing a space between said support and said face to receive a portion of the width of a length of corrugated material, the corrugations thereof being perpendicular to the free edge of said plate, a bending strip hinged to said support in close proximity to said edge to seat under the projecting width of said material to be bent along the line of said free edge, handle means on said plate for lifting said plate while said material is placed thereunder, handle means on said strip to line score and bend said material along the free edge of said plate, a gauge member mounted on said strip to define the width of the projecting portion of said material, and means to adjust said gauge relative to said plate to define a predetermined line of bend on said material.
